SHOE

Theodore Gutwein, Dayton, Ohio

Application December 3, 1936, Serial No. 114,027

6 Claims. (Cl. 36—30)

This invention relates to shoes, while its distinguishing feature resides in a filler of novel construction and arrangement inserted between the insole and outsole of the shoe.

5 The object of the invention is to provide a filler of soft rubber, so arranged and attached as to provide a shoe which is comfortable to the wearer without added bulk in any of the parts of the shoe, which will be durable and which will be economical to manufacture.

10 Specific advantages are inherent in the invention, many of which will be apparent from the following detail description taken in connection with the accompanying drawings.

15 Fig. 1 is a bottom view, partly in section, of a shoe of the McKay type embodying the invention;

Fig. 2 is a cross section on line 2—2, Fig. 1;

20 Fig. 3 is a plan view of an inner sole with the filler attached to the insole, as used in Fig. 1;

Fig. 4 is a bottom view, partly in section, of a Goodyear welt shoe embodying the invention;

25 Fig. 5 is a cross section on line 5—5, Fig. 4; and,

Fig. 6 is a cross section on line 6—6, Fig. 4.

The embodiment shown in Fig. 1 includes certain conventional elements of a McKay shoe, including an upper 1 having a lining 2 with

30 inner edges 3 turned over the edges of an insole 4. It includes an outsole 5, which is attached to the upper by a line of stitches 6 passing through the insole, the inturned edges 3 of the upper, and the outsole.

35 The McKay shoe, as illustrated in Fig. 1, may be constructed according to the ordinary methods of manufacture except as to the insertion of the novel filler section, which includes a layer of fabric 7 upon which is superimposed a layer of

40 soft or sponge rubber 8.

The fabric 7 may be co-extensive in size with the forepart of the insole while the rubber layer 8 may be of a size and so positioned as to lie wholly within the inturned edges 3 of the upper.

45 The layer of rubber may have its edges bevelled, as shown at 9. The rubber layer is preferably attached to the fabric 7 by a line or lines of stitches 10, and the filler strip so prepared may then be attached by cement to the insole 4.

50 After the insole has been so combined with the filler strip a series of perforations 11 may be stamped through the rubber, the fabric and the insole for purposes of ventilation. Actual practice has shown that the use of these perfo-

rations passing through at least the insole, and preferably also through the fabric and rubber, adds materially to the comfort of the shoe preventing the foot from heating.

5 In lasting a shoe of the McKay type, as shown in Figs. 1 to 3, staples 12 passing through and engaging the edge 3 of the upper, the fabric 7 and the insole 4 may preferably be used. In bottoming the shoe a line of stitches 6 will engage the insole, the outsole and pass through the outer edge of the fabric 8 as well as the inturned edge 3 of the upper.

10 The embodiment shown in Figs. 4, 5 and 6, apart from the construction and arrangement of the filler section, embodies the conventional features of a Goodyear welt shoe. It includes an upper 14 having its edge turned over the edge of an insole 15 and secured by a line of stitches or an inseam 16 to a flange portion 17; the stitches 16 also engaging a welt 18. An outer sole 19 is attached to the upper by a line of stitches 20 passing through the outsole and the welt.

15 The embodiment specifically shown in the drawings has a nailed heel seat. The inturned edges of the upper being secured by tacks 21 which engage the insole 15. The outer sole and a heel lift 22 may be attached to the upper by nails 23.

20 In the Goodyear welt shoe, as shown in Figs. 4, 30 5 and 6, a filler section is constructed similar to that described in connection with the preceding figures. A layer of rubber 24 is superimposed upon a layer of fabric 25, to which it is attached by a line of stitches 26. In either type of shoe 35 it is a matter of choice whether the filler member extends throughout the entire length of the shoe or not. In Figs. 1, 2 and 3 it is illustrated as covering only the forepart while in the embodiment shown in Figs. 4, 5 and 6 it is illustrated 40 as extending throughout the length of the shoe.

45 The rubber section 24 is smaller in extent than the fabric section 25, thereby leaving an edge 27 about the rubber. This extended edge 27 of the fabric is cut somewhat smaller than the contour of the sole of the finished shoe but it is of such an extent as to be engaged by the stitches 20 passing through the outer sole and the welt. As shown in the drawings, the extended edge 27 extends uniformly around the entire shoe, but this is a matter of choice since this extended edge may consist only of a plurality of ears which may be engaged in spots by the stitches 20. The embodiment specifically shown in Figs. 50 55

4 and 6 has a nailed heel seat. In such a case the edge 27 at the heel will be tucked under the inturned edge of the upper and will be engaged by the tacks 21, which pass through the 5 edge of the upper and into the insole. If, however, a sewed seat is used the edge 27 of the fabric will be arranged at the heel section of the shoe as it is arranged at the forepart, that is, it will lie between the welt and the outer sole to be engaged by the line of stitches attaching the outer sole to the welt.

In both embodiments, as specifically shown in the drawings, the layer of rubber is first attached by stitches to the layer of fabric so that the 15 filler section is a unitary structure. This filler section is then cemented to the insole. In the McKay structure the filler section is attached to the insole before the shoe is lasted, the edges of the upper being turned over the edge of the 20 fabric as well as the edge of the inner sole. In the Goodyear welt shoe the filler unit is cemented to the insole after the insole has been attached to the upper. Thus, in the embodiment specifically shown the rubber is stitched 25 to the fabric by long loose stitches while the filler unit including both the rubber and the fabric are initially attached to the insole by cement.

It will be obvious, however, that in certain 30 processes of shoe manufacture, which differ from or which are modifications of the prevailing types, other specific means of attachment may be desirable. Thus it may be desirable to attach the rubber to the fabric by a cement rather than by 35 stitches. Or, it may be desirable to attach the rubber, the fabric and the insole together by the same stitches with or without the use of cement. In the use of a cutout insole where a shoe is made according to the Sbicca method it is desirable to secure these parts together, that is 40 the insole, the rubber and the fabric, all by a line of stitching extending about the cut-out portion of the insole.

It is desirable to use stitching as an attaching means for uniting the rubber with the fabric 45 whether those stitches also pass through the insole or not, because the stitches prevent the rubber from creeping when the shoe is warm much more effectively than does cement. But a satisfactory shoe can be made by the use of 50 cement for securing the rubber to the fabric. In most methods of shoe manufacture a line of stitches is used for uniting the outsole to the upper and in that case that line of stitches may engage the fabric. Thus, in the McKay shoe, 55 as shown in Figs. 1, 2 and 3, the stitches 6 unite the outsole with the upper and also engage the fabric and in the Goodyear welt shoe, illustrated in Figs. 4, 5 and 6, the stitches 16 secure the 60 outsole to the welt and also pass through and engage the margin 27 of the fabric. It is recommended, therefore, that at least one of the attaching means for holding the filler strip in place be a mechanical means such as stitches or staples, although this is not absolutely necessary 65 in order to obtain a serviceable shoe because shoes manufactured without the use of stitches and entirely by cementing have been found satisfactory.

The use of fabric as a backing for the sponge 70 rubber layer and secured to it prevents the rubber from creeping and secures a uniform layer of rubber throughout the life of the shoe. In addition, the fabric serves as an attaching means by having an edge extending outwardly beyond 75 the rubber layer which may be engaged by tack-

ing means, at points where the inclusion of the rubber layer would result in unnecessary bulk.

Sponge rubber for purpose of a filler between the insole and outsole is already a commercial product so that its characteristics need not be 5 described to those skilled in the art. It is usually one-eighth inch thick or less. The fabric should be a tough, closely woven piece of goods and unyielding. Shoe drill is satisfactory for this purpose but a cloth which is prepared specially for airplane construction and known as airplane cloth has been found to be preferable because of its strength and unyielding qualities without unnecessary bulk.

It is to be noted that in the McKay shoe, as 15 specifically illustrated in Figs. 1, 2 and 3, the fabric is placed adjacent the insole while in the Goodyear welt type, illustrated in Figs. 4, 5 and 6, the fabric is placed adjacent the outsole. The reason for this will be apparent from an 20 inspection of the drawings, because in the one case the edge of the fabric is secured adjacent the insole while in the other case the fabric is secured adjacent the outsole. The particular 25 type of shoe and the particular method employed in making it will usually determine whether the fabric should be adjacent the outsole or adjacent the insole.

The advantages of a shoe employing this invention should be obvious from the foregoing 30 description. The rubber insert, which is securely held in position, gives a soft cushion for the foot and the particular structure prevents the rubber or filler from creeping and piling up in ridges or lumps, while the method of its attachment 35 enables the shoe to be manufactured without including the rubber in the principal seams of the shoe where any unnecessary bulk would produce a clumsy shoe.

The preferred method of applying the invention 40 has been illustrated and described in detail, but it will be obvious from the foregoing description that various changes may be made in the details of construction, within the scope of the appended claims, without departing from 45 the spirit of this invention and that parts of the invention may be used to advantage without the whole.

I claim:

1. In a shoe having an outer sole, an inner 50 sole and an upper having its marginal edges extending over the edge of the inner sole and positioned between said soles, the combination comprising a cushion member inserted between said soles and consisting of a layer of sponge rubber 55 superimposed upon a layer of fabric, the rubber being smaller in extent than the fabric, a seam of fasteners securing the fabric to the rubber, the layer of rubber being so proportioned and positioned as to lie wholly within the edges of 60 the upper, and means for securing the fabric beyond the rubber to at least one of said soles.

2. In a shoe having an outer sole, an inner 65 sole and an upper having its marginal edges extending over the edge of the inner sole and positioned between said soles, the combination comprising a cushion member inserted between said soles and consisting of a layer of sponge rubber superimposed upon a layer of fabric, the rubber being smaller in extent than the fabric, a seam 70 of fasteners securing the fabric to the rubber, and stitches securing the outer sole with the shoe and passing through the fabric beyond the rubber.

3. In a shoe having an outer sole, an inner

sole and an upper having its marginal edges extending over the edge of the inner sole and positioned between said soles, the combination comprising a cushion member inserted between said soles and consisting of a layer of sponge rubber superimposed upon a layer of fabric, the layer of rubber being smaller in extent than the layer of fabric, a seam of fasteners securing the fabric to the rubber, the edge of the fabric extending between the inturned edge of the upper and the inner sole, and means for securing the fabric beyond the rubber to the upper.

4. In a shoe having an outer sole, an inner sole and an upper having its marginal edges extending over the edge of the inner sole and positioned between said soles, the combination comprising a cushion member inserted between said soles and consisting of a layer of sponge rubber superimposed upon a layer of fabric, the layer of rubber being smaller in extent than the layer of fabric, a seam of fasteners securing the fabric to the rubber, and stitches uniting the outer sole, the inner sole and the upper and passing through the fabric beyond the rubber.

5. In a shoe having an outer sole, an inner sole and an upper having its marginal edges extending over the edge of the inner sole and positioned between said soles, the combination comprising a cushion member inserted between said soles and consisting of a layer of sponge rubber and a strip of fabric extending beyond the rubber, a seam of fasteners securing together the fabric, rubber and inner sole, and stitches passing through the outer sole, inner sole, marginal edges of the upper and that part of the fabric extending beyond the rubber.

6. In a welt shoe the combination comprising an outer sole, an inner sole, an upper having its marginal edges extending over the inner sole and positioned between said soles, a cushion member inserted between said soles and consisting of a layer of sponge rubber and a strip of fabric extending beyond the rubber, a seam of fasteners securing the fabric to the rubber, and stitches securing the outer sole to the welt and passing through the fabric beyond the rubber.

THEODORE GUTWEIN.
